UPHOLSTERY CONSTRUCTION

Charles Edward Lenz, Jr., Baltimore, Md., and
Rutledge A. Parker, Waterbury, Conn.

Application May 2, 1935, Serial No. 19,476

7 Claims. (Cl. 155—179)

This invention relates to new and useful improvements in upholstery construction, such as seat structure for chairs, couches, etc.

Among the several objects of the invention are to provide means for supporting the webbing in its normal position, and whereby the webbing will not pull away from the seat frame; to provide one or more rods arranged directly under the webbing for supporting the latter as well as the foundation springs; to provide such rods with upwardly extending eyes for receiving the bottom convolutions of said springs to thereby secure the latter against displacement; to provide said eyes with upwardly extending points for assisting in projecting the eyes upwardly through the webbing; to provide each rod with an adjustable portion whereby the rod may be readily fitted to a standard sized frame; and to provide each rod with an upstanding attaching eye at each end whereby the same may be readily attached to the opposite inner faces of the frame.

With these and other objects in view which will more fully appear, the nature of the invention will be more clearly understood by following the description, the appended claims, and the several views illustrated in the accompanying drawings.

In the drawings:

Figure 1 is a top plan view of a chair frame showing a seat constructed in accordance with our invention.

Figure 2 is a bottom plan view thereof.

Figure 3 is a vertical section taken on the line 3—3 of Figure 1.

Figure 4 is a vertical section taken on the line 35 4—4 of Figure 1.

Figure 5 is a view similar to Figure 2, but showing a modified form of supporting rod.

Figure 6 is a perspective view showing one of the rods illustrated in Figures 1 to 4.

Figure 7 is a perspective view showing one of the rods illustrated in Figure 5.

Figures 8 and 9 are perspective views showing modified forms of eyes mounted on the supporting rod.

Figure 10 is an enlarged fragmentary vertical sectional view showing a modified form of attaching means; and

Figure 11 is a view taken at right angles to Figure 10.

Like reference numerals designate corresponding parts throughout the several figures of the drawings.

Referring to the drawings, our invention includes a supporting frame A which in this instance is a chair having front legs 5, 5 and rear

legs 6, 6. The seat supporting frame includes a front wall 7, a rear wall 8, and side walls 9, 10. It will be understood that the frame A illustrates but one type of frame to which our supporting rods may be applied.

A webbing B of burlap, canvas, or other suitable material, preferably of one-piece, is stretched tightly across the frame and is secured along all of its marginal edges to the lower faces of the frame walls by tacks 11 or other suitable means. Thus the webbing in its normal position does not extend above the lower edges of the frame. Several rows of foundation springs C are supported on the webbing A, and are adapted to be connected together at their upper ends and to the frame by the usual means.

It is well known in the art that a one-piece webbing for supporting a plurality of foundation springs embodies more desirable flexibility than is inherent in a webbing formed by crossed straps. However with either form of webbing employed, a sagging thereof will be produced whenever a load is placed on the foundation springs. We have, therefore, provided a plurality of supporting rods D which extend across the frame below the webbing B and have their ends attached to the walls of the seat frame. These rods are respectively disposed under the rows of foundation springs and cooperate with the webbing B to afford additional support for the springs whereby the amount of sagging of the webbing will be reduced to the minimum and yet permit of said webbing retaining the desired flexibility.

The rods D are disposed directly below the webbing B and are attached to the frame A in a manner to support said webbing in its normal position as shown particularly in Figures 3 and 4. In the preferred construction shown in Figures 1 to 4, and 6, each rod D is bent intermediate its ends at a plurality of points to form upwardly extending eyes 12 which are arranged in pairs, the openings of the eyes being in a plane at right angles to the length of the rod. The end portions of the rod are bent upwardly as at 13, 13 and terminate in attaching eyes 14, 14. The eyes 14, 14 are projected upwardly through the webbing B and are positioned against the inner faces of the front and rear walls 7 and 8 by nails 15, 15. In order to facilitate projecting the eyes 12 and 14 upwardly through the webbing B, we have pointed each eye as at 16. Each rod is bent intermediate the rearmost eye 12 and the attaching eye 14 to form an adjustable portion E which as shown in these Figures 1 to 4, and 6, comprises connected zig-zag lengths which are arranged

in a common plane and in the same plane as the fabric. This adjustable portion E permits the rod to be readily assembled on standard frames of different dimensions within certain limits. This 5 adjustable portion E will also permit the rod to bow downwardly with the webbing B when the latter is placed under a load. By means of the eyes 12, the lower convolutions of the foundation springs C may be readily threaded thereinto and 10 by this means the springs are adapted to be quickly and securely attached to the supporting rods and retained in their proper spaced positions.

In the form illustrated in Figures 5 and 7, each 15 supporting rod F is provided with a plurality of pairs of eyes 12a and with attaching eyes 14a, 14a at its ends. The eyes 12a are preferably pointed as at 16a whereas the attaching eyes 14a are left in the same plane as the body portion 20 of the rod and are adapted to be attached to the lower faces of the front and rear walls 7 and 8 of the frame A by nails 17 or other suitable fastening means. This rod F is bent intermediate its ends to form spaced zig-zag shaped adjustable portions G which are disposed in a common plane and in the plane of the webbing B.

Instead of forming the foundation spring attaching eyes 12 and 12a by coiling the same from the rod as shown in Figures 1 to 7, we may employ 30 a rod H wherein the eyes are formed by bending the rod upwardly into an inverted U form as shown at 18 and surrounding each eye with a collar 19 as shown in Figure 8.

In Figure 9, we have illustrated a still further 35 form wherein a plurality of eyes 20 are formed by a wire which has its ends wound around the rod I.

In Figures 10 and 11 we have disclosed a further modification wherein additional means are 40 provided for securing the ends of the rod J to the front wall 7 of the frame. The end of the rod J is formed into an eye 21 which is secured to the under face of the wall 7 by a nail 22 or other suitable means. The maximum load imposed 45 on the seat is adjacent the front wall and in order to provide against the nail 22 pulling out, we employ a hanger 23 which is formed of stamped metal to provide an attaching body which is secured to the inner face of the front 50 wall 7 at a point directly above the webbing B by nails 24. The lower end of the body is provided with spaced compression spring receiving sockets 25, 25 directly above the webbing, and with a centrally disposed tongue 26 which projects 55 downwardly through an opening or slit 27 in the webbing and is formed with an eye or opening 28 for receiving the rod J and thereby provide a secondary support for the end of said rod.

It is of course to be understood that the details 60 of structure and arrangements of parts may be variously changed and modified without departing from the spirit and scope of our invention.

We claim:

1. Upholstery construction comprising a frame 65 having marginal walls, of a webbing secured to the walls thereof, and a rod extending across the frame below the webbing, one end of the rod being supported by a hanger attached to the inner face of the associated wall and projecting 70 downwardly through the webbing to engage the rod, said hanger being provided with an eye above the webbing to receive a compression spring, the end of the rod being formed into an eye disposed below the associated wall of the frame and 75 attached to said wall.

2. Upholstery construction comprising a frame, a yieldable webbing secured along its marginal edges to said frame and normally disposed in a single flat plane, a supporting spring-steel rod directly attached at its ends to opposite walls of the frame, said rod being normally disposed in a plane parallel to the webbing and located directly under and in contact with said webbing, and a foundation spring seated on the webbing directly above the rod whereby both the webbing and the rod support said spring, said rod being formed with a pair of spaced eyes projecting upwardly through the webbing for receiving the lower convolution of the spring, said rod being also provided with a longitudinally yieldable portion located between one attaching end of the rod and said pair of eyes.

3. Upholstery construction comprising a frame, a yieldable webbing secured along its marginal edges to said frame and normally disposed in a single flat plane, and a supporting rod directly attached at its ends to opposite walls of the frame, said rod being normally disposed in a plane parallel to the webbing and located directly under and in contact with said webbing, said rod being longitudinally yieldable whereby the rod will bow downwardly co-extensively with the webbing when weight is placed upon the latter, said rod being bent intermediate its attaching ends into a zig-zag shape to form a longitudinally yieldable portion, said zig-zag portion being flat and disposed in a plane parallel to the webbing.

4. Upholstery construction comprising the combination with a frame, and a yieldable webbing of vegetable fibre secured along its marginal edges to said frame and normally disposed in a single flat plane, of an attachment therefor comprising a one-piece supporting metallic rod directly attached at its ends to opposite walls of the frame, said rod being normally disposed in a plane parallel to the webbing and located wholly and directly under and in contact with said webbing, said rod being longitudinally yieldable whereby the rod will bow downwardly co-extensively with the webbing when weight is placed upon the latter, said rod being provided with a pair of spaced eyes projecting upwardly through the webbing, and a foundation spring seated on the webbing directly above the rod and having its lower convolution engaged in said spaced eyes whereby said spring is supported by both the webbing and the rod and the spring is retained against movement relative to the rod, said rod being bent intermediate one attaching end and said pair of eyes into a zig-zag shape to form a longitudinally yieldable portion, said zig-zag portion being flat and disposed in a plane parallel to the webbing.

5. Upholstery construction comprising the combination with a frame, and a yieldable webbing of vegetable fibre secured along its marginal edges to said frame and normally disposed in a single flat plane, of an attachment therefor comprising a one-piece supporting spring-steel rod directly attached at its ends to opposite walls of the frame, said rod being normally disposed in a plane parallel to the webbing and located wholly and directly under and in contact with said webbing, said rod being longitudinally yieldable whereby the rod will bow downwardly co-extensively with the webbing when weight is placed upon the latter and then return to normal position when relieved of said weight, said rod being provided with a pair of spaced eyes projecting upwardly through the webbing, and a foundation spring

5 seated on the webbing directly above the rod and having its lower convolution engaged in said spaced eyes whereby said spring is supported by both the webbing and the rod and the spring is retained against movement relative to the rod, said eyes being pointed upwardly to facilitate the projection of the eyes through the webbing.

10 6. Upholstery attachment comprising a one-piece supporting rod having attaching means at its ends, the rod intermediate its ends being formed into a pair of eyes projecting in the same general direction for receiving the lower convolution of a foundation spring, said rod between one end and said eyes being bent into a zig-zag

shape to form a flat and longitudinally yieldable portion.

7. Upholstery attachment comprising a one-piece supporting rod having attaching means at its ends, the rod intermediate its ends being formed into a pair of eyes projecting in the same general direction for receiving the lower convolution of a foundation spring, said rod between one end and said eyes being bent into a zig-zag shape to form a flat and longitudinally yieldable portion, said eyes projecting in the same general direction and having pointed upper ends.
